UNITED STATES PATENT OFFICE.

ALBERT J. GORDON, OF PAWHUSKA, OKLAHOMA, ASSIGNOR OF ONE-FOURTH TO E. B. COLWELL, ONE-FOURTH TO EDMUND COLWELL, AND ONE-FOURTH TO CLARK F. GROSS, ALL OF MONMOUTH, ILLINOIS.

PLAYER-PIANO.

1,359,054.

Specification of Letters Patent. Patented Nov. 16, 1920.

Application filed March 16, 1920. Serial No. 366,189.

To all whom it may concern:

Be it known that I, ALBERT J. GORDON, a citizen of the United States, residing at Pawhuska, in the county of Osage and State of Oklahoma, have invented certain new and useful Improvements in Player-Pianos, of which the following is a specification.

This invention relates particularly to pneumatic actions for player pianos. Ordinarily hammers of such instruments are actuated by what are called "pneumatics" involving the use of individual bellows for each key and hammer, such bellows being operated by a main pneumatic, or bellows connected with a suction box or air chest which communicates with all of the hammer operating bellows. Such pneumatic devices are complicated and not durable. I have found that the individual pneumatics or bellows may be dispensed with and their place taken by much simpler appliances which are much more durable.

According to my invention I provide a tracker bar a suction box, or air chest, and a main bellows for creating a partial vacuum in the suction box as heretofore, but instead of connecting the suction box with a series of pneumatics or bellows as heretofore, I connect it with a suitable number of valve chests provided with valves and pistons for controlling the inlet and exhaust of air from the chest and the actuation of the hammer operating mechanism. The valve chests are of such construction and are so applied to the suction box that they may be quickly removed individually when defective without disturbing the other parts of the mechanism, and may be readily replaced by perfect ones.

In the accompanying drawings:—

Figure 1 shows a vertical section of a player piano with my improvements applied.

Fig. 2 is a top plan view of a portion of the suction box with a plurality of my improved appliances supported thereby.

Fig. 3 shows a rear elevation of the parts shown in Fig. 2.

Fig. 4 is a perspective view showing a portion of the suction box, one of the devices constructed in accordance with my invention for operating the hammers, and a portion of a lever connecting the appliance with a wippen forming part of the hammer

action. Fig. 4 also illustrates how conveniently one of the devices may be connected with or removed from the suction box without disturbing companion members. 55

Fig. 5 is a sectional view showing connection between the tracker bar and valve chest, and showing also how the valve chest is connected with the suction box. In this figure the parts are in normal position.

Fig. 6 is a view similar to Fig. 5, but shows the parts in a different position when an aperture in the tracker bar is opened by the note sheet and when the action is operated to sound a note.

Fig. 7 shows a section on the line 7—7 of Fig. 5. 70

Fig. 8 is a perspective view of one of the valves controlling communication between the suction box and a piston chamber.

I have shown my improvements applied to a player piano in general of well known 75 or conventional construction. The action air chest or suction box A is connected by a tube B with a bellows C which may be operated by treadle mechanism D or in other ways. By operating the bellows C, air is 80 drawn from the suction box and a partial vacuum is produced therein. e indicates a tube which may be led to a motor for operating the note sheet. The keys E operate in the usual way to actuate the jacks F 85 which in turn operate the hammers G.

The tracker bar is indicated at H and the note sheet at I. Instead of connecting the tracker bar with individual bellows for the hammer action I connect each opening h in 90 the tracker bar by a tube J with a casing K of novel construction and which is connected with the suction box as hereinafter explained.

Each valve chest K comprises a casing 95 made of any suitable material having a part 1 connected directly with the suction box, and a part 2 which rests on top of the box. The part 1 contains a chamber 3 into which extends the stem 4 of a valve 5 which operates in a chamber 6 above the chamber 3 and below an opening 7 in the top wall of the part 1. The chamber connects through an opening 8 with the suction box. Below the chamber 3, a pressure chamber 9 100 is provided which connects with a tube J, and this chamber is covered by a flexible diaphragm 105.

The part 2 contains a piston chamber 11 in which operates a piston 12 arranged below an opening 13 in the casing and this piston is carried by a rod or stem 14 which 5 supports a valve 15 and is connected with a lever 16 which operates a jack F and thus actuates a hammer. The rod 14 is loosely connected to the piston 12 in order that it may tilt when raised and lowered, while the 10 piston moves properly in the piston chamber. The piston 12 is provided with bleed holes α' through which air may slowly pass during the operation of the mechanism.

It will be understood that there is a valve 15 chest for each hammer and for each tube J and in general the operation of the mechanism is similar to that of other player pianos.

Fig. 5 shows the normal condition of the 20 mechanism when a channel h is closed by the note sheet. At this time the valve 5 is closed and a communication between the suction box and the piston chamber 11 is closed, and as the chamber 11 is open to the atmosphere through the opening 7, the piston is held in its uppermost position by atmospheric pressure and by the hammer mechanism. If now the note sheet be moved to uncover the channel h as indicated in Fig. 30 6, air will enter the chamber 9 and raise the valve 5, thus opening communication between the suction box and the piston chamber 11 and producing a partial vacuum in said chamber, causing said piston to be 35 quickly moved inward and thus actuate the lever 16. As indicated, there is a small bleed opening α through the diaphragm 10 so that air may pass slowly between the chambers 3 and 9. Inasmuch as there are small holes α' 40 through the piston 12, air can pass through the piston when the valve 5 is first opened, but the suction is sufficient to draw the piston inward and to close the valve 15 at this time. After the valve 15 has closed the 45 opening 13, a partial vacuum will be produced between the piston 12 and the valve 15, air being drawn into the chamber 11 through the holes α' .

When a channel h is closed by the note 50 sheet, the diaphragm 10 falls, the valve 5 is lowered, and connection is cut off between the piston chamber 11 and the suction box, and air enters the opening 7 and causes the piston 12 to raise and at the same time the 55 valve 5 is closed. By providing an opening 7 to the atmosphere, it will be observed air can enter the chamber 11 after communication with the suction box is cut off, so that the piston may rise. When the piston 12 60 is drawn inwardly to its full extent, the valve 15 closes the opening 13 so that the partial vacuum produced in the manner before described beneath the piston may have its full effect. By providing the piston 12 65 with the holes α' , provision is made for

producing a partial vacuum between the piston and the valve 15 when the parts are in the position shown in Fig. 6. During this operation of raising the piston, it will be understood that when air first enters the 70 chamber 11 it passes through the holes α' and enters the chamber 11 above the piston. At the same time atmospheric pressure acting on the bottom of the piston raises the latter in the manner before described. 75

All of the appliances just described and thus constructed operate in the same way. Figs. 2 and 3 illustrate how the appliances are supported on the suction box and it will be observed that each one of them is a separate unit and may be withdrawn and replaced without disturbing the others. Fig. 4 shows this more clearly. It will be observed that the suction box A is formed with ports a , each of which is adapted to 80 communicate with a port 8 in a valve chest. Each valve chest preferably rests on a felt packing N and each valve chest is attached to the suction box by screws O entering the rear side of the part 1 of the valve chest, 85 extending through said part 1, and entering holes σ in the suction box. The rods or valve stems 14 are detachably connected with the lever 16 as clearly indicated in the drawings.

The bellows mechanism C shown in Fig. 90 1 is of well known construction and its construction and operation need not be specifically described. Any suitable bellows mechanism may be substituted for that shown.

As indicated in Fig. 1, the valve chests 100 are applied to the rear side of the suction box opposite the removable section S of the casing so that when this section is removed ready access is afforded to said chests and they may be very quickly removed and replaced.

I claim as my invention.

1. The combination with the suction box, 110 tracker bar and hammer of a player piano, of a valve chest having a valve chamber and a piston chamber open on one side to the atmosphere, a valve controlling the connection between the suction box and the piston chamber, means operated by air admitted at the 115 tracker for opening said valve to establish communication between the suction box and the piston chamber, a piston in the piston chamber, a valve operated thereby to close communication between the piston chamber and the atmosphere, and connections between the piston and a hammer. 120

2. The combination with the suction box, 125 tracker bar, and hammer of a player piano, of a valve chest having a valve chamber, a pressure chamber, and a piston chamber, means for connecting the pressure chamber with the tracker bar, a valve controlling communication between the suction box, the piston chamber, and the atmosphere, a pis- 130

ton operating in the piston chamber, means for connecting the piston with a hammer, a port in the piston chamber above the piston, and a valve controlling said port.

5. 3. The combination with the suction box, the hammers, and the tracker bar of a player piano, of a plurality of valve chests detachably and individually connected with the suction box and each containing a valve
10 chamber, a piston chamber, and a pressure chamber, a valve in the chest for controlling communication between the suction box and the piston chamber, a piston operating in the piston chamber, and means for detachably connecting said piston with a hammer operating mechanism.

4. The combination with the suction box, the tracker bar, and the hammers of a player piano, of a plurality of valve casings, each comprising two parts, one of which contains a valve chamber, and the other a piston chamber, a valve operating in the valve chamber, a piston operating in the piston chamber, and means extending through the
25 side of the first part and engaging the side of the suction box for detachably connecting the valve chest with said box.

5. In a player piano, the combination of a

casing having a removable rear section, a suction box within the casing, a tracker bar, 30 hammers mounted in the rear portion of the casing, a plurality of valve casings attached to the rear side of the suction box in front of the removable section of the casing, bellows arranged in the lower portion of the casing, 35 connections between the suction box and said bellows, and connections between the valve casings and the tracker bar.

6. The combination with the suction box, tracker bar, and hammers of a player piano, 40 of a valve chest having a valve chamber and a piston chamber, a valve controlling the connection between the suction box and the piston chamber, means operated by air admitted at the tracker for operating said valve, a piston in the piston chamber having an opening through it, to establish communication between opposite ends of the piston chamber whereby a partial vacuum is produced on both sides of the piston and 45 50 connections between the piston and a hammer.

In testimony whereof, I have hereunto subscribed my name.

ALBERT J. GORDON.
